UNITED STATES PATENT OFFICE.

CHARLES F. ROTHWEILER, OF SEATTLE, WASHINGTON.

PARTITION.

1,211,760.

Specification of Letters Patent.

Patented Jan. 9, 1917.

Application filed June 2, 1915. Serial No. 31,773.

To all whom it may concern:

Be it known that I, CHARLES F. ROTHWEILER, a citizen of the United States, residing at Seattle, in the county of King and State of Washington, have invented certain new and useful Improvements in Partitions, of which the following is a specification.

This invention relates to partitions and to devices for securing the same in place within drawers, pigeon holes, etc., to divide the same into smaller compartments.

The object of the invention is the provision of devices of this character which may be readily applied, and effective in operation.

The invention consists in the novel construction and combination of parts, as will be hereinafter described and claimed.

In the accompanying drawings, Figure 1 is a plan view of a drawer or the like with the present invention applied therein. Fig. 2 is a transverse vertical section through 2—2 of Fig. 1. Fig. 3 is a perspective view of a sheet of material or stock from which the partitions are obtained by cutting or breaking the same at selected grooves provided in the sheet. Figs. 4, 5 and 6 are perspective views of various forms of partition fasteners shown detached.

The stock from which the partitions are obtained is in the nature of a metal plate, Fig. 3, having parallel top and bottom edges 10 and vertical grooves or scores 11 disposed in the opposite faces of the plate. The scores are disposed in spaced relations, say one inch, apart, to afford weakened sections whereat the plate may be bent at right angles or at which the plate may be broken into predetermined lengths.

In the spaces or panels between the adjacent scores I provide, as shown in Figs. 2 and 3, holes 12 and 12¹ disposed preferably in horizontal rows adjacent to top and bottom edges 10 of the plate, as shown in Figs. 2 and 3. Provided for use in selected ones of said plate holes are studs 13, 14 and 15 having bodies of substantially cylindrical forms which are adapted to fit tight into the holes where employed.

The studs 13 are each provided, as shown in Fig. 4, with a slot 16 extending from one end to near its other end. The studs 15 have slots 16¹ which extend from both ends (Fig. 6) to within a short distance of their midlengths. The other studs 14, Fig. 5, are

each provided with a head 17 at one end and with a slot 16² extending from its other end into proximity to the head.

The operation of the aforescribed parts may be explained by explaining an application thereof to a drawer as illustrated in Figs. 1 and 2. In these views, A and B represent the sides and ends of a drawer which is to be divided by a longitudinal partition C into two compartments, which, in turn, are to be divided by transverse partitions D, E, F and G. To these ends, I break or sever at the proper scores 11 of plate (Fig. 3) pieces of the same to be inserted between the drawer sides B and designated by H. The partition C may likewise be of this length but, as shown in Fig. 1, it is provided with a terminal flange C¹ which is formed by making the piece into a panel length greater than required to fit between the end walls B and turning such panel into rectangular relation to the main part of the partition. The other partitions D, E, F and G are broken from the plate to suitable lengths and have their ends engaged in the slots 16, 16¹ or 16² of the coupling studs. The studs 13 are utilized where a connection is to be made between the outer pieces H, and the transverse partitions, by inserting the stud ends which are unprovided with slots in the former and engaging the transverse partitions in the stud slots. The headed studs 14 are employed to fasten the transverse partitions, as F and G, to a longitudinal partition when the transverse partitions are not aligned. Where the transverse partitions, as D and E, are in alignment, the studs 15 are used at their juncture with the partition C to couple such aligned partitions and also secure them to the referred to longitudinal partition. In their manufacture, the studs are swaged to cause the bifurcations thereof to be formed into bow shapes, as represented in Figs. 4, 5 and 6, to afford resilient fingers to embrace the partition ends which are forced therebetween. When the end of a partition is inserted in a stud slot, the stud is slightly spread to further increase its holding power within the hole in which the stud has been inserted. After the partitions has been assembled, they may, if desired, be fastened to the containing drawer or structure by nails or screws, as denoted by 19 in Fig. 1, such fastening means extending through se-

lected ones of the holes 12 or 12¹ (Fig. 3) of the outer pieces H and also of the flange element C¹.

What I claim, is—

5. 1. In combination, a partition member of the class described, provided with a series of spaced holes, slotted studs adapted to be received by the holes of said partition member, and a second partition member adapted 10 to have an end thereof engage in the slots of said studs whereby the partition members are coupled together.
15. 2. In devices of the class described, the combination with partition members provided with series of spaced holes, of studs adapted to be inserted in selected ones of said holes, said studs being provided with slotted extremities to receive the end of a partition member disposed in rectangular 20 relation to the partition member in which are inserted said studs.
25. 3. In devices of the class described, a rec-

tangular plate formed with spaced grooves extending across the opposite faces of the plate to provide relatively weak lines at 25 which the plate may be broken into predetermined lengths, said plate being provided with holes in the spaces intermediate the adjacent of said grooves for the reception of coupling studs.

30 4. A partition structure comprising a plurality of transversely and longitudinally arranged partitions, and slotted studs extending through the transverse or longitudinal partitions to receive the ends of the other 35 partitions whereby all of the partitions are connected rigidly together.

Signed at Seattle, Washington, this 26th day of April, 1915.

CHARLES F. ROTHWEILER.
